UNITED STATES PATENT OFFICE.

SEBASTIEN LACAVALERIE, OF NEW YORK, N. Y.

GARTER.

Application filed January 9, 1922. Serial No. 528,126.

To all whom it may concern:

Be it known that I, SEBASTIEN LACAVALERIE, citizen of France, residing at New York, in the county of New York and State 5 of New York, have invented certain new and useful Improvements in Garters, of which the following is a specification.

This invention relates to garters, having more particular reference to garters adapted 10 for use in supporting men's socks.

The invention has for an object to provide a novel and inexpensive form of garter presenting no projecting parts and capable of quick attachment to and removal from the 15 sock.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of a garter constructed according to 25 my invention, showing the same in extended position.

Fig. 2 is a similar view showing a modified form of garter.

Fig. 3 is a detail perspective view of the 30 fastening clip of a further modified form of garter.

Fig. 4 is a detail side view showing the type of garter illustrated in Fig. 1 as in actual use.

Fig. 5 is a similar view to Fig. 4 but showing the application of type of garter illustrated in Fig. 2.

Fig. 6 is a detail face view showing a clip with a modified arrangement of the sock 40 gripping element.

As here embodied my improved clip comprises briefly, a clip adapted to engage the sock, a strap or band attached to the clip, and a hook attached to the band and adapted 45 to engage the clip to hold the garter in place.

In the embodiment of the invention shown in Figs. 1 and 2 the clip comprises a thin flat disk 10 which may be made of metal, or 50 rigid nonmetallic material such as celluloid, and which is formed with a circular hole or aperture 11 in the centre thereof.

Leading inward toward this hole from one side of the disk 10 is a tapered notch 12 55 the walls of which are at an acute angle to one another, the inner end of this notch

communicating with the hole 11 by means of a short and very narrow slit 13.

The band is indicated at 15 and may be of ordinary elastic webbing such as is in 60 common use on garters, being attached to the disk 10 by passing the end thereof through a slot 16 cut in the disk.

The opposite end of the band carries the hook which is here shown as comprising a 65 plate or body 17 from one side of which a narrow integral hook 18 projects, the plate being slotted as at 19 for attachment of the band 15. The ends of the band may be turned back upon the main body thereof 70 and secured to the latter by stitching or any other suitable means, or I may arrange one end for expansion and contraction of the band in a well known manner.

In the use of my improved garter the 75 clip 10 is placed on the top edge of the sock, which enters through the notch 12 and slit 13, being gripped in the said slit 13 and prevented from withdrawal. The band 15 is then placed around the limb of the 80 user and the hook 18 inserted in the aperture 11. To remove the clip from the sock the parts thereof on opposite sides of the passage leading into the aperture 11 are sprung in opposite directions transversely 85 to the body of the clip until the walls of slit 13 are separated a sufficient distance from each other for removal of the sock.

In the embodiment of the invention shown in Fig. 2 I utilize the clip 10 but instead 90 of the flat elastic webbing 15 I provide an endless elastic band 20 of circular cross section which is attached to the clip by looping it through the aperture 11. The hook employed in this modification comprises an 95 elongated plate 21 having at one end a rearwardly pointing tongue 22 which is curved so as to incline toward the plate 21 near its tip and leave a space at its root in which the band is looped. The operative length 100 of the band may be varied by looping it one or more times around the tongue 22. The opposite end of the plate 21 is formed with a hook 23 which is adapted to engage the band 20 as indicated in Fig. 5. In this 105 construction the slot 16 in disk 10 may be omitted if desired.

In the modification shown in Fig. 3 I provide an elongated plate 25 vertically slotted at its lower end as at 26 to provide a 110 pair of guides on which a horizontal bar 27 is guided. At its upper end this plate 25

is provided with a rectangular opening 28 into a lower corner of which a diagonal slot 29 leads. This slot 29 permits of ready engagement of the end of the band 30 with the 5 plate 25 after the band has been placed around the limb of the user. The top of the sock or stocking is inserted in the lower end of slot 26 and gripped by the bar 27.

In Fig. 6 I have shown a clip 10^a having a central hole 11^a and a tapering notch 12^a, this notch terminating in a slit 13^a which is preferably curved as shown. The walls of this slit may be serrated or roughened to more securely grip the sock, which 15 is engaged throughout the full length of the slit 13^a, this extended engagement ensuring a firm hold of the clip on the sock and obviating any chance of the sock becoming disengaged.

20 It is to be understood that various other changes and modifications might be made in my improved garter without departing from the spirit and scope of the invention.

Having thus described my invention what 25 I claim as new and desire to protect by Letters Patent of the United States is as follows:

1. A garter comprising a clip formed of a thin plate provided with an aperture and 30 having a slit leading into said aperture from one side of the plate, a band attached to said clip, and a hook attached to said band, said

hook being adapted to engage in the said aperture to hold the garter in position.

2. A garter comprising a clip formed of 35 a thin plate formed with an aperture and having a slit leading into said aperture from one side of the plate, a band engaged in said aperture, and a hook attached to said band and adapted to be engaged in said aperture to hold the garter in place.

3. A garter comprising a clip formed of 40 a thin plate formed with an aperture and having a slit leading into said aperture from one side of the plate, a band engaged in said aperture, and a hook attached to said band and adapted to be engaged in said aperture to hold the garter in place, the outer portion of said slit being in the form of a tapering notch.

4. A garter comprising a clip formed of 45 a thin plate formed with an aperture and having a slit leading into said aperture from one side of the plate, a band engaged in said aperture, and a hook attached to said band and adapted to be engaged in said aperture to hold the garter in place, the outer portion of said slit being in the form of a tapering notch, the inner portion of said slit being longitudinally curved.

50 In testimony whereof I have affixed my signature.

SEBASTIEN LACAVALERIE.
